UNITED STATES PATENT OFFICE.

ANDREW P. TALLMADGE, OF WASHINGTON, DISTRICT OF COLUMBIA, ASSIGNOR OF
ONE-HALF TO WILBER R. GARRETT, OF WASHINGTON, DISTRICT OF COLUMBIA.

FLOOR WAXER.

Application filed June 20, 1928. Serial No. 296,881.

This invention relates to new and useful improvements in waxing devices, and particularly to devices for applying wax to floors.

One object of the invention is to provide a device of this character which includes novel means for feeding the wax to the floor engaging fabric.

Another object is to provide novel and improved means for maintaining the handle of the device in proper position, for operating the waxer over the floor, while at the same time permitting such handle to be used to force the wax in the direction of the floor engaging fabric.

Another object is to provide means which permit the handle being raised and lowered, during the operation of the device, and at the same time permit the handle to feed the wax to the floor engaging fabric.

Other objects and advantages will be apparent from the following description when taken in connection with the accompanying drawings.

In the drawings:

Figure 1 is a side elevation of a floor waxing device, made in accordance with the present invention, the side portions of the felt cover being shown in section.

Figure 2 is a vertical longitudinal central sectional view through the device.

Figure 3 is a top plan view of the device, the handle and supporting device therefor being broken away, as indicated by the line 3-3 on Figure 1.

Figure 4 is a transverse sectional view on the line 4-4 of Figure 1.

Figure 5 is a horizontal sectional view on the line 5-5 of Figure 2.

Figure 6 is a transverse sectional view on the line 6-6 of Figure 2.

Figure 7 is a plan view of the felt retaining frame.

Referring particularly to the accompanying drawings, 10 represents a block of suitable material which has its four sides beveled, as clearly shown in the drawings. On the upper face of the block there is formed an elevated portion 11, which produces the surrounding ledge of shoulder 12, the purpose of which will presently be explained. On the forward portion of the elevation 11 there is formed an upwardly and rearwardly inclined boss 13, in which is formed a recess 14, receiving the lower end of the wax containing cup 15. The lower end of the cup is provided

with a discharge nipple 16, which is screwed into the upper end of the wax feeding and distributing channel or bore 17. This bore, as illustrated in the drawings, flares downwardly and laterally, and has its lower end opening through the bottom of the block, to distribute the wax to the felt covering 20 of the block. This felt covers the lower face of the block, and extends upwardly on all of the four sides of the block, where its marginal edges are secured to the upper face of the before-mentioned shoulder 12, beneath the frame 21. This frame is illustrated, in detail, in Figure 7. While I have illustrated a fan-shaped channel or bore 18, I wish it understood that I may provide a plurality of independent channels leading from the upper end of the bore, and discharging into the lower end thereof. This is an obvious modification, and forms no particular part of the present invention. Therefore, such modification is not illustrated.

Extending transversely of the end portions of the upper face of the elevation 11 are the upwardly and outwardly inclined ribs 22 and 23. Disposed outwardly of the felt covering, and extending longitudinally beneath the bottom of the block, is a strip of canvas or other suitable fabric, shown at 24, and having its ends brought upwardly over the front and rear inclined or beveled faces of the block, and engaged respectively with the said ribs 22 and 23. A wire clamp, in the form of a rectangular frame 25, has one end engaged with the forward rib 22, with the adjacent end of the fabric 24 thereunder, while the other end of the wire frame engages the other end of the fabric 24 with the other rib 23. This last-named end of the frame 25 is in the form of a transverse shaft 26, having its ends cranked, as at 27, while the intermediate portion is formed with a handle 28, whereby to cause a binding action between the frame and the ribs 22 and 23, to securely hold the fabric ends in stretched position on the block.

A wire yoke 29 has the ends of its arms turned inwardly, as at 30, to be seated in the recesses 31 formed in the opposite sides of the before-mentioned boss 13. The bight portion of the yoke is bent, as at 32, to partly encircle the handle rod 33, and to frictionally retain such position whereby to move upward and downwardly with the handle rod. Disposed within the wax cup 15, and

having its stem extending upwardly through the screw cap 34 of the cup, is a plunger 35, arranged to force the wax out through the nipple of the cup. The lower end of the handle rod 33 is connected with the upper end of the stem by means of the universal joint 36. This joint permits the handle to be moved upwardly and downwardly, or laterally, as desired, while at the same time permitting free rotation of the handle, to move the plunger downwardly in the cup. It will be noted that the plunger is threaded into the cup, whereby to necessitate the rotation of the handle to force the wax from the cup. The lower portion of the felt covering 20 is formed with an opening 20', which registers with the lower end of the passage 18, of the block, so that the wax, delivered from the cup, will be applied to the fabric strip, and not to the felt. The fabric applies the wax to the floor, as will be understood, by passing the device backwardly and forwardly over the floor. When more wax is needed, the operator simply rotates the handle, whereby to advance the plunger, and force more wax out through the channel or passage 18, to the fabric. If, however, more wax is forced out, than is necessary, the operator can rotate the handle in a reverse direction, which lifts the plunger, thereby producing a suction in the cup, which withdraws the excess wax back into the cup. The use of the universal joint permits the operator to force the wax from the cup, as needed, without stopping the operation of the device. In devices heretofore, it was necessary to stop the operation, and so position the handle with respect to the wax cup, that the wax could be forced out.

40 By swinging the handle 28, of the fabric

clamping frame 25, upwardly, the frame will be loosened whereby to permit removal of such fabric and placing of a new piece. Attention is directed to the fact that the handle 28 is illustrated as extending upwardly onto the top of the block. This handle may extend downwardly, if desired, without changing the spirit or intent of the invention. It may also be stated that the sides of the fabric may be brought up on the sides of the base block, and held beneath the longitudinal side bars of the frame 25.

The felt covering 20 serves as a cushion between the block and the floor, to which wax is to be applied, so that no injury to the floor may result, especially in view of the fact that said base block is preferably formed of metal, whereby to utilize the weight thereof to press the fabric firmly against the surface of the floor.

What is claimed is:

A device for applying wax to a floor including a block, a wax container mounted on the block, a plunger threaded in the container having a stem, a handle rod having universal connection with the stem whereby to permit rotation of the plunger from any position of the handle, and a yoke mounted on the block for vertical swinging movement and having its bight portion formed with a resilient open loop frictionally embracing the handle rod whereby to prevent lateral pivotal movement of the rod while permitting vertical pivotal movement thereof during the operation of the device, and disengagement of the handle rod whereby said handle rod may be completely removed with the stem and plunger of the wax container.

In testimony whereof, I affix my signature.
ANDREW P. TALLMADGE.
